 P. H. Murphy Company, New Kensington, Pa.,
 a corporation of Pennsylvania

Application March 5, 1937, Serial No. 129,107

10 Claims.

(Cl. 108—5)

This invention relates to metal car roofs of the type having hatchways extending therethrough. The principal objects of the present invention are to provide such hatchways with metal hatch frames that can be readily applied to existing roofs without material alterations thereof, to provide for the ready removal and replacement of the hatch frames without disturbing the roof sheets and to provide for simplicity and economy of construction. The invention consists in providing the roof with a cover sheet adapted to be superimposed on the hatch sheet thereof and provided with a hatch frame adapted to register with the hatch opening in said hatch sheet.

15 In the accompanying drawings, which form part of this specification and wherein like symbols refer to like parts wherever they occur,

Fig. 1 is a plan view of a portion of a car roof provided with a hatch construction embodying my invention.

20 Fig. 2 is an enlarged vertical transverse section through one-half the roof at one of the hatchways on the line 2—2 in Fig. 1.

Fig. 3 is a vertical longitudinal section through the roof at one of the hatchways on the line 3—3 in Fig. 1.

25 Fig. 4 is an enlarged fragmentary section similar to Fig. 2 through one side of the hatch construction.

30 Fig. 5 is an enlarged fragmentary section similar to Fig. 3 through one side of said hatch construction.

Fig. 6 is a fragmentary cross-section through the roof at the eaves, the section being taken through one of the depressed end portions of the cover sheet on the line 6—6 of Fig. 1; and

35 Fig. 7 is a perspective view of one end portion of the cover sheet with the hatch frame detached therefrom.

40 The car roof illustrated in the accompanying drawings comprises end and intermediate roof sheets 1 and 2, respectively, that extend from side plate 3 to side plate 3 of the car with their eaves ends supported on and secured, as by rivets 4, to the outstanding top flanges of eaves angles 5, whose depending flanges are suitably secured to the upstanding inner side flanges of said side plates. The end and intermediate roof sheets are provided with depending eaves flanges 6, which overhang the outer edges of the eaves angles 5 and upstanding side marginal flanges 7 that are straddled by a seam cap 8 that is suitably secured to said flanges. At the end of the car, the end sheet 1 is supported on and suitably secured to the outstanding top flange of an angle

9 whose depending flange is suitably secured to an end plate 10.

As shown in Fig. 1, the end roof sheet 1, herein-after referred to as the hatch sheet, has one or more hatch openings therein which lead into the interior of the car through a wooden hatch frame 11 located below said opening and supported between two wooden carlines 12. Each wooden hatch frame is provided with a sheet metal lining 13; and the hatch sheet is provided around the hatch opening therein with a flange 14 that is bent downwardly over the upper margin of said lining. The roof is provided with a ceiling 15 and has a suitable roof insulation 16 interposed between said ceiling and the roof sheets.

Superimposed on the hatch sheet 1 is a metal cover sheet A that extends from end to end of the hatch sheet and has depending eaves flanges 17 that overhang the depending eaves flanges 6 thereof and hatch openings that register with the respective hatch openings therein. Mounted in each of the hatch openings in the cover sheet A is a metal hatch frame B that extends below said cover sheet into the flanged hatch opening in the hatch sheet 1 and upwardly above said cover sheet where it terminates in an outstanding flange 18 that constitutes a seat for a hatch cover (not shown). As shown in the drawings, the metal hatch frame B is rigidly secured to the cover sheet A by a weld 19 of added metal that extends continuously around the hatch opening therein in the angle between said frame and the upper surface of said sheet.

The cover sheet A is preferably of inverted channel-shaped cross-section with outstanding side marginal or base flanges 20 at the lower edges of its side walls that bear upon the hatch sheet 1 from end to end thereof. As shown in the drawings, said cover sheet has depressed end portions 21 that rest on the hatch sheet above the eaves angles 5 and are held down on said hatch sheet by the rivets 4 that secure the latter to said angles. These depressed portions 21 are adapted and arranged to form downwardly opening hollow ribs 22 adjacent to and midway of the side margins of said cover sheet. As shown in the drawings, these ribs 22 of the cover sheet are curved downwardly and merge into the depending eaves flanges 17 thereof, which flanges are offset outwardly opposite said ribs to provide drainage and ventilating openings 23 between ends of the cover sheet and hatch sheet.

By the arrangement described, the hatch frame B is rigidly secured to the cover sheet A and has its lower end portion fitting in the flanged hatch

opening in the hatch sheet 1 without being secured thereto, thereby permitting the cover sheet and hatch frame assembly to be quickly and easily applied to the car roof without material alteration thereof. The cover sheet can be readily removed without removing the hatch sheet and without disturbing the main hatchway construction of the roof merely by shearing the rivets 4 that secure the cover sheet and hatch sheet 10 to the eaves angles 5. The channel-shaped cross-sectional shape of the cover sheet increases its rigidity and load carrying capacity; and the hollow ribs 22 of said sheet serve to stiffen and strengthen the eaves end portions thereof and 15 provide for ventilation and drainage.

What I claim is:

1. A car roof having a hatch opening therein and a member superimposed on said roof and extending from eaves to eaves thereof, said member 20 having a hatch frame rigid therewith registering with said hatch opening.

2. A car roof having a hatch opening therein, a member superimposed on said roof and extending from eaves to eaves thereof, said member having 25 a hatch opening therein above the hatch opening in said roof, and a hatch frame supported in the hatch opening in said member and registering with the hatch opening in said roof.

3. A car comprising side plates, a roof supported 30 on said side plates and having a hatch opening therein, a member extending from side plate to side plate above said roof, and a hatch frame sustained by said member and registering with said hatch opening.

35 4. A car comprising side plates, a roof sheet spanning from side plate to side plate and having a hatch opening therein, a cover sheet spanning from side plate to side plate above said roof sheet, said cover sheet having a hatch opening therein 40 above the hatch opening in said roof sheet, and a hatch frame secured in the hatch opening in said cover sheet and registering with the hatch opening in said roof sheet.

5. A car comprising side plates, a roof sheet 45 spanning from side plate to side plate and having a hatch opening therein, a cover sheet spanning from side plate to side plate above said roof sheet, said cover sheet having a hatch opening therein above the hatch opening in said roof sheet, and a hatch frame secured in the hatch opening in said cover sheet and registering with the hatch opening in said roof sheet, said cover sheet being of substantially inverted channel-shaped cross-section.

55 6. A car comprising side plates, a roof sheet spanning from side plate to side plate and having a hatch opening therein, a cover sheet spanning

from side plate above said roof sheet, said cover sheet having a hatch opening therein above the hatch opening in said roof sheet, and a hatch frame secured in the hatch opening in said cover sheet and registering with the hatch opening in 5 said roof sheet, said cover sheet being provided with downwardly offset side marginal flanges that rest on said roof sheet.

7. A car comprising side plates, a roof sheet extending from side plate to side plate and having a hatch opening therein, a cover sheet extending from side plate to side plate above said roof sheet, said cover sheet having a hatch opening therein above the hatch opening in said roof sheet, and a hatch frame mounted in the hatch 10 opening in said cover sheet and extending downwardly into the hatch opening in said roof sheet.

8. A car comprising side plates, a metal roof sheet extending from side plate to side plate and having a hatch opening therein, a metal cover sheet extending from side plate to side plate above said roof sheet, said cover sheet having a hatch opening therein above the hatch opening in said roof sheet, and a metal hatch frame welded in the hatch opening in said cover sheet and extending downwardly into the hatch opening in said roof sheet, said cover sheet having downwardly offset side marginal portions that rest on said roof sheet.

30 9. A car comprising side plates, a metal roof sheet extending from side plate to side plate and having a hatch opening therein, a metal cover sheet extending from side plate to side plate above said roof sheet, said cover sheet having a hatch opening therein above the hatch opening in said roof sheet, and a metal hatch frame secured in the hatch opening in said cover sheet and extending downwardly into the hatch opening in said roof sheet, said cover sheet having downwardly offset side marginal flanges and depressed end 35 portions that rest on said roof sheet.

30 10. A car comprising side plates, a metal roof sheet extending from side plate to side plate and having a hatch opening therein, a metal cover sheet extending from side plate to side plate above 45 said roof sheet, said cover sheet having a hatch opening therein above the hatch opening in said roof sheet, and a metal hatch frame secured in the hatch opening in said cover sheet and extending downwardly into the hatch opening in said 50 roof sheet, said cover sheet having downwardly offset side marginal portions that rest on said roof sheet, said cover sheet having depressed portions at its ends that rest on and are secured to said roof sheet and hollow ribs between said depressed 55 portions.
